UNITED STATES PATENT OFFICE.

GEORGE A. KNAPP, OF CHICAGO, ILLINOIS, ASSIGNOR TO KNAPP BROTHERS MANUFACTURING COMPANY, A CORPORATION OF ILLINOIS.

METAL FACING FOR INSIDE OF WINDOW-OPENINGS.

1,393,792.

Specification of Letters Patent.

Patented Oct. 18, 1921.

Application filed February 18, 1921. Serial No. 446,018.

To all whom it may concern:

Be it known that I, GEORGE A. KNAPP, a citizen of the United States, residing at Chicago, in the county of Cook and State of Illinois, have invented certain new and useful Improvements in Metal Facings for Inside of Window-Openings, of which the following is a specification.

This invention relates to metal facing for inside of window openings.

One of the objects of the invention is to provide a smooth, protecting facing for window openings inside of rooms.

Another object is to provide protecting covers for the corners at the juncture of the wall and the surface bounding the window opening which has the appearance of being a continuation of the plaster, extending to the jamb at the termination of the reveal and stool and which is flush with the plaster at the edge of the trim thus provided, whereby to make a storm-tight covering, that is, sanitary in its lack of openings to harbor insects; which is durable and artistic in appearance, dust-proof and which serves as a finishing ground for the plaster.

Another object is to provide a knock-down metallic structure including a trim, stool and reveal in one, that can be easily put together on the job thus saving excessive storage and freight charges and contributing to ease and convenience of handling and installing.

Other, further and more specific objects of the invention will become readily apparent, to persons skilled in the art, from a consideration of the following description, when taken in conjunction with the accompanying drawings, wherein:

40 Figure 1 is a vertical section through a window and wall bounding the opening showing the invention.

Fig. 2 is an enlarged sectional view of the bottom of Fig. 1.

45 Fig. 3 is a section taken on line 3—3 of Fig. 4.

Fig. 4 is an elevation of a rear view of the device.

In all the views the same reference characters are employed to indicate similar parts.

The structure for one window consists of two curved sheet metal uprights 5 and similar metal end pieces 6 for the top of the opening and 7 for the bottom of the open-

ing, or the stool and trim. The side pieces and upper end pieces constitute a trim 8 and reveal 9 joined by an intermediate curved part 10.

The lower cross piece 7 may be used alone 60 to provide a combined stool 11 and trim 12.

The curved sheet metal pieces 5, 6 and 7 are joined together by corner brackets 13, having ledges 14 to receive the ends of the reveals and trim portions so that they will 65 be flush with the exposed surface of the brackets giving the appearance of unbroken surfaces.

Each of the brackets has lugs 15 projecting over the ledges to which to secure the 70 sheet iron parts. The lugs have clearance holes for attaching screws 16. The screws may be of the flat head type, preferably welded to the inner surface of the sheet to register with the holes in the lugs and held 75 in place by nuts 17.

The sheet metal parts may, if desired, have holes through which the screws may pass into threaded lugs, if such arrangement is preferable, and sight of the screw 80 heads is not objectionable, but such variation is not so artistic in appearance as when the heads of the screws are not shown.

The outer edges of the finished sides are perforated and bent at an angle something 85 more than ninety degrees to form a knee for the plaster, as at 18, and which also serves as a ground to which to finish the plaster 19 so that the trim 12 and the plaster will be flush in the finished wall. The 90 returned flat part 20, of the edge of the trim, is to be nailed to strips 21, or to the wall. The inner edge 22 of the stool may be fastened with screws 23 below a jamb strip 24, for the window 25.

In applying the overlying stool 7 it is well to first float the ledge with cement or plaster 26 before the part 7 is put in place and then force the material through the openings 27 to completely back up the overlying metal sheet.

The sheet metal members have a flat portion constituting the trim and another flat portion at right angles to the trim constituting the reveal and a curved portion connecting these two parts.

The edge of the trim is inturned and out-turned to form a knee for a ground by which to finish the plaster, the inturned part terminating in a flange 28 to receive nails to se- 110

cure the outer edges to the wall structure, the inturned portion being perforated through which perforations to key the plaster.

- 5 5 The structure described and claimed herein, while referred to as a covering for a window opening, is equally well adapted to serve the same purpose for a door opening and the word window as used in the claims 10 is descriptive and not qualifying.

While I have herein shown a single embodiment of my invention, it will be understood that changes may be made in the configuration and disposition of the parts within 15 the scope of the appended claims.

Having described my invention, what I claim as new and desire to secure by Letters Patent, is:—

1. A covering for a window opening comprising a rectangular frame consisting of four sheet metal members, each member longitudinally bent near its transverse median region to provide a reveal and a trim located at substantially right angles to each other, 25 the edges of the trim bent inwardly to provide a knee to serve as a finishing ground and bent again to provide a flange to receive attaching nails; corner brackets connecting the terminal ends of the members, the adjoining surface of the brackets being substantially flush with the inner surfaces of the members, the inner edge of the reveal extending sufficiently to be under the jamb strips of the window frame.
2. An inside covering for an opening in a wall comprising a knock-down rectangular frame having a plurality of sheet metal members, each member longitudinally bent into a curve near its transverse median region 40 to provide a reveal and a trim located at substantially right angles to each other, the edges of the trim being perforated and bent at an angle greater than ninety degrees to form a knee and bent again to form an attaching flange, the intermediate portion of the bent part spacing the knee a uniform distance from the wall, whereby the knee serves as a ground for the plaster; screws

suitably spaced apart near the ends of the members; and brackets to connect adjacent ends of said members providing holes to receive the screws and to hold adjacent members that are located at right angles to each other.

3. A structure having a sheet metal member and a bracket to which it is to be attached and screws permanently secured to the surface of the sheet metal member adjacent the bracket to be received by holes in the bracket and nuts on the screws to hold said member and bracket together without exposing the screws.

4. A covering for a window opening comprising a rectangular frame providing four sheet metal members, each member longitudinally bent near its transverse median region to provide a reveal and a trim located at substantially right angles to each other, the longitudinal edges of the trims bent inwardly to provide a knee to serve as a finishing ground for the plaster to be applied to the wall whereby the knees and plastered surfaces will be substantially flush and means to secure said trims to the wall, spaced away therefrom, the inner edges of the reveal extending sufficiently to lie under the jamb strips of the window frame.

5. A covering for a window opening comprising a rectangular frame providing four sheet metal members each member longitudinally bent near its transverse median region to provide a reveal and a trim located at substantially right angles to each other, the longitudinal edges of the trim bent inwardly to form a knee to serve as a ground for the plaster to be applied to the wall whereby to bring the plaster flush with the trim; means to space the knee uniformly away from the wall; means to secure the trim to the wall, said reveal extending sufficiently to lie under the jamb strips of the window frame.

In testimony whereof I hereunto subscribed my name.

GEORGE A. KNAPP.
